UNITED STATES PATENT OFFICE.

CHARLES E. HARTHAN, OF LYNN, MASSACHUSETTS, ASSIGNOR TO THE GENERAL ELECTRIC COMPANY, OF NEW YORK.

ELECTRIC-ARC LAMP.

SPECIFICATION forming part of Letters Patent No. 635,851, dated October 31, 1899.

Application filed April 23, 1898. Serial No. 678,549. (No model.)

To all whom it may concern.

Be it known that I, CHARLES E. HARTHAN, a citizen of the United States, residing at Lynn, county of Essex, State of Massachusetts, have 5 invented certain new and useful Improvements in Electric-Arc Lamps, (Case No. 660,) of which the following is a specification.

This invention relates to inclosed electric-arc lamps, and has reference to the mechanism for adjusting and regulating the arc.

The invention has for its object to provide an improved construction and arrangement of mechanism by means of which the electric arc will be positively established and automatically regulated during the operation of the lamp, and comprises certain combinations of parts, all of which will hereinafter be particularly pointed out and distinctly claimed.

In the accompanying drawings, Figure 1 is 20 a view in elevation of the arc-governing mechanism. Fig. 2 is a side view taken at right angles to that in Fig. 1. Fig. 3 is a diagram illustrating the circuits of the lamp.

The carbon-regulating mechanism is mounted 25 on a frame A, having at its bottom the centrally-located raised base portion B, with the tubular passage-way b. At the top of the frame A is a corresponding tubular passage-way a. The carbon-feed rod C extends 30 through the passage-ways a and b. Suspended from the top of the frame A are the series-magnet coils D and the shunt-magnet coils E, arranged in pairs. The series magnets are provided with movable cores d, mounted 35 on a cross-piece D'. A like construction is employed for the shunt-magnets, e e representing the cores' and E' the cross-pieces upon which the cores are mounted. Depending from the frame A and on the opposite sides of 40 the carbon-feed rod are lugs c. Pivoted to these lugs is a lever F, having an open central portion surrounding the carbon-feed rod, the pivotal connection being made at opposite sides of the central opening.

A link G is pivoted at one end between ears f on one end of the lever F and at the other end between ears g, fixed to the upper side of the cross-bar E' between its ends. The cross-bar D' is similarly connected with the opposite 45 end of the lever F by link H. The upper end of the link H is pivoted within a slot in the

end of the lever F, while its lower end is pivoted to ears h on the cross-bar D'.

A lever K, having a bifurcated end k, is pivoted to the clutch-supporting sleeve L. The 55 other end of the lever K is connected by a link M to depending lugs i on the frame A. The levers F and K are provided with elongated slots and are connected by a link I, having its ends pivoted in the slots. The link 60 H, above referred to, passes freely through the slot within which the lower end of the link I is pivoted.

In order that the series magnets D shall always be in condition to strike the arc when 65 the lamp is not energized, it is necessary that the core of the magnet be withdrawn when no current is passing. In the construction shown this object is effected by the downward pull on the link I due to the weights supported 70 thereby. To equalize the pull exerted by the magnets D on its core D', a compensating spring S" is adjustably connected at s to the base of the frame A and at the other end is connected to an arm H', projecting from the 75 link H.

Since the series and shunt magnets act in opposition to each other in moving the carbon-feeding rod, any substantial variation in the current through or difference of potential 80 of the arc has a tendency to cause a reciprocation of the feeding-rod, known as "pumping," the same being due to the inertia of the reciprocating parts. To overcome this tendency, a dash-pot N is operatively connected 85 to the feeding mechanism, which dash-pot has its cylinder pivoted to an arm G', extending from the link G. The plunger of the dash-pot is fixed to the base of the frame A at n.

The clutch mechanism consists of a hollow 90 cylinder or sleeve L, having an inturned upper edge loosely surrounding the carbon-feeding rod. The inturned edge is indicated in Fig. 1 by dotted lines. Extending from opposite sides of the cylinder L are ears O with drooping ends. Each of these ears has a pivot p, which engages a slot in one end of a bell-crank lever P, which lever is extended around so as to clear the feeding-rod C and is fulcrumed at r in an open frame Q. The frame 95 Q has an oblong opening therein surrounding the carbon rod and the grip-shoes J and at

either end a lug R, slidably engaging the reduced upper portion T of posts U, fixed to the base of the frame A. The other arms V of the bell-crank levers are pivoted to grip-5 shoes J.

On the under side of the cross-bar D' is an insulated contact-block X for closing the circuit between the terminals Y and Z. The circuit is closed only when the core of the 10 magnet D is in its lowest position.

A diagram of the circuits of the lamp is shown in Fig. 3. The current entering at x passes through the steadyng resistance x' and then during the normal operation of the lamp 15 through the series coil D. The current then divides, the major portion passing through the arc and thence to the negative terminal y of the lamp, while the other component of the current passes through the coil E in shunt 20 to the arc and then to the negative terminal. A resistance y' is connected in a normally-open shunt-circuit about the coils D and E.

A device for short-circuiting any number of spires of the coiled resistance x' for purposes of adjustment is conventionally represented at x².

The operation of the lamp is as follows: Upon closing the switch S' the current passes through the series coil D, which attracts its 30 core d. The motion of the core is then transmitted through the links H and I to the lever K, which then acts to lift the cylinder L. The pivot-pins p, carried by the cylinder L, then act on the bell-crank levers P to turn 35 them about their fulcrums r, thus causing the grip-shoes J to bite the feeding-rod C. A further upward movement of the sleeve L raises the feeding-rod and so springs the arc, the difference of potential of which results in 40 energizing the shunt-coils E. These coils attracting their cores e act through the link G and lever F in opposition to any upward movement of the feeding-rod. The force of attraction of the coils E increases with the 45 length of the arc, and the mechanism is so proportioned and adjusted as to reach a condition of balance when the desired length of arc has been attained. Upon opening the switch S' the arc is extinguished, the armature D' of the series magnet falls, and the insulated contact-point X bridges the contacts 50 Y Z, thus shunting the resistance y' about the actuating-coils E and D.

What I claim as new, and desire to secure 55 by Letters Patent of the United States, is—

1. In an electric-arc lamp, a frame, two sets of magnets pendent therefrom, movable cores for said magnets, a lever fulcrumed to the frame and connected by links with said cores, 60 a second lever in operative relation to the

first lever, a link for connecting one end of the second lever with the frame, a clutch carried by said last-mentioned lever, and a feeding-rod actuated by said clutch.

2. In an electric-arc lamp the combination 65 of a rod, a sleeve loosely surrounding such rod, ears extending from said sleeve, vertically-extending guide-rods with reduced upper ends, an open frame slidably mounted on said guide-rods, bell-crank levers fulcrumed in said frame, a grip-shoe carried by one arm of each bell-crank lever, and a sliding connection between the other arm of each bell-crank lever and one of said ears.

3. In an electric-arc lamp, the combination 75 of a frame, guide-rods extending upwardly therefrom, a frame-piece movable on said guide-rods, a sleeve, bell-crank levers pivoted to said frame-piece and having one set of arms pivoted to said sleeve, and grip-shoes 80 carried by the other arms.

4. In an electric-arc lamp, the combination of a frame, a forked lever having a link connection with said frame, a sleeve carried by 85 said forked lever, ears extending from said sleeve, a frame-piece, bell-crank levers fulcrumed in said frame-piece, a grip-shoe carried by one arm of each bell-crank lever, and a connection between the other arm of each bell-crank lever and one of said ears, and 90 means for actuating said forked lever.

5. In an electric-arc lamp the combination 95 of a sleeve pivotally connected to a floating lever, ears extending therefrom, bell-crank levers having a loose connection with said ears and fulcrumed in a frame-piece, and grip-shoes carried by said levers.

6. In an electric-arc lamp, the combination 100 of a frame, two sets of magnets fixed thereto, movable cores for said magnets, a lever fulcrumed to the frame and connected by links with said cores, a second lever, a link, for connecting one end of the second lever with the frame, a link connecting said levers, a 105 carbon-feeding rod, a sleeve loosely surrounding said rod, and a pivotal connection between the sleeve and said second lever.

7. In an electric-arc lamp, the combination 110 of a frame, two sets of magnets pendent therefrom, movable cores for said magnets, a lever fulcrumed to the frame and connected by links with said cores, arms extending from each link, a dash-pot connected to one arm and a spring acting on the other.

In witness whereof I have hereunto set my 115 hand this 20th day of April, 1898.

CHARLES E. HARTIAN.
